UNITED STATES PATENT OFFICE.

STACY B. HASELTINE, OF CHICAGO, ILLINOIS, ASSIGNEE TO WILLIAM H. MINER, OF CHAZY, NEW YORK.

YOKE FOR DRAFT-RIGGING.

1,286,304.

Specification of Letters Patent. Patented Dec. 3, 1918.

Application filed April 13, 1916. Serial No. 90,836.

To all whom it may concern:

Be it known that I, STACY B. HASELTINE, a citizen of the United States, residing at Chicago, in the county of Cook and State of Illinois, have invented a certain new and useful Improvement in Yokes for Draft-Rigging, of which the following is a full, clear, concise, and exact description, reference being had to the accompanying drawings, forming a part of this specification.

This invention relates to improvements in yoke for draft riggings.

For several years past, the railroads have been desirous of obtaining a draw-bar and yoke connection which will avoid slotting of the sills and at the same time be readily detachable. Furthermore, the railroads are demanding a yoke connection of the above character which is adapted to all types of standard draw-bars whether the latter have coupler key slots or not. A further requisite demanded by the railroads is a detachable draw-bar and yoke connection so arranged that all the parts are easily accessible and wherein the draw-bar may be removed or replaced without disturbing the gear proper.

The object of my invention is to provide a yoke for railway draft riggings of simple construction and which will embody all the advantageous features above indicated.

In the drawing forming a part of this specification, Figure 1 is a part side elevation, part vertical longitudinal section of a yoke showing my improvements in connection therewith. Fig. 2 is a horizontal sectional view of the structure illustrated in Fig. 1 and taken on the line 2—2 thereof. Fig. 3 is a front end elevation of the yoke. And Fig. 4 is a detail perspective of one of the locking blocks employed.

Referring to said drawing, 10 denotes a standard draw-bar having the usual butt 11 provided with upper shoulder 12 and lower shoulder 13. The yoke A, which as shown is preferably a steel casting, is provided with upper arm 14, lower arm 15, rear connecting piece 16, and a hollow, boxlike hood or head 17 at its front end, the hood being open at the front and provided with side walls 18—18, and upper wall 19, the upper wall 19 being provided on its inner face with an integral, transversely extending gib or shoulder 20, the latter being adapted

to coöperate with the upper shoulder 12 of the draw-bar. Within the yoke a shock absorbing member is illustrated conventionally by dotted lines, the shock absorber shown in the drawing being a well known type of friction gear.

The lower wall 21 of the hood is downwardly offset from the lower arm 15 of the yoke, so that when the locking block is removed the draw-bar may be let down and pulled outwardly clear of the shoulder 20.

To support the draw-bar butt in position and prevent it from pulling out under draft, I have provided a locking block 22 having an upstanding shoulder 23 which coöperates with the lower shoulder 13 of the draw-bar. The block 22 is extended downwardly at its front end as indicated at 24 and is thereby adapted to bear against the transversely extending wall 25. To further provide backing for the block when the yoke is operated under draft, the side walls 18—18 are provided with inwardly extending integral shoulders or abutments 26 against which the ends of said shoulder 23 of the block abut. To support the block 22 in proper position, I have provided a right angled relatively narrow key 27 which extends through a slot 28 in the block and has its rear end supported on the shelf or ledge provided by the wall 21, (see Fig. 1.)

The downwardly extending arm 29 of the key preferably fits within a groove 30 cut in the transversely extending wall 25 so that the key lies flush with the front wall of the yoke at the bottom thereof. Any suitable means may be provided for detachably retaining the key in place and for this purpose I have illustrated a cotter 31.

To permit the draw-bar to move radially of the yoke, the upper shoulder or gib 20 is convexly curved on its inner face as indicated at 32, and the block similarly curved as indicated at 33.

To disassemble the parts, the cotter 31 is first removed, then the key 27 is withdrawn forwardly and finally the block 22 is taken out from the under side of the hood. Thereupon, the draw-bar may be dropped so as to clear the shoulder 20 and then withdrawn forwardly.

Although I have herein shown and described what I now consider the preferred means of carrying out my invention, the

same is merely illustrative and I contemplate all changes and modifications that come within the scope of the claims appended hereto.

5 I claim:

1. A yoke provided with a hooded forward end within which is adapted to be received a shouldered draw-bar butt, said yoke being provided with means arranged 10 to engage the upper shoulder of a draw-bar butt, and devices, coöperable with the lower shoulder of a draw-bar butt, for detachably locking the yoke to a draw-bar, said devices including a shouldered block 15 arranged to engage the lower shoulder of a draw-bar butt, and a key for supporting said block in position, said key being insertible from the front end of the yoke and supported at its front end and at its rear 20 end by integral portions of the lower wall of said hooded end.
2. A yoke provided with a hooded forward end within which is adapted to be received a shouldered draw-bar butt, said 25 yoke being provided with means arranged to engage the upper shoulder of a draw-bar

butt, and devices, coöperable with the lower shoulder of a draw-bar butt, for detachably locking the yoke to a draw-bar, said devices including a shouldered block insertible 30 through an opening in the bottom wall of the hood, and a key applied from the front end of the yoke, said key comprising a right angled member having one arm thereof extending downwardly and the other extending horizontally through said block and into engagement with the yoke at the inner end of the block.

3. A cast steel yoke for draft riggings, said yoke having a rectangular hollow head, 40 the bottom wall of which is provided with an opening, a shouldered locking block insertible and removable through said opening, and a right angled key for retaining said block in position, said key passing 45 through a slot in said block and supported at its rear end by an integral shoulder of the yoke.

In witness that I claim the foregoing I have hereunto subscribed my name this 15th 50 day of March, 1916.

STACY B. HASELTINE.
